UNITED STATES PATENT OFFICE

163,715

DUMP BODY TAIL GATE UNIT

Edwin A. Schonrock, San Angelo, Tex.

Application November 6, 1950, Serial No. 12,860

Term of patent 7 years

(Cl. D14—3)

To all whom it may concern:

Be it known that I, Edwin A. Schonrock, a citizen of the United States, residing at San Angelo, in the county of Tom Green and State of Texas, have invented a new, original, and ornamental Design for a Dump Body Tail Gate Unit, of which the following is a specification, reference being had to the accompanying drawing, forming part thereof.

Figure 1 is a perspective view of a dump body tail gate unit, showing my new design;

Figure 2 is a top plan view;

Figure 3 is a side elevational view thereof, and Figure 4 is a front elevational view of the same.

The dotted line portion is for illustrative purposes to indicate environmental use only.

I claim:

The ornamental design for a dump body tail gate unit, as shown and described.

EDWIN A. SCHONROCK.
